GRAF CORPORATION OF AMERICA, OF NEW YORK, N. Y., A CORPORATION OF
NEW YORK

ADVERTISING APPARATUS

Application filed July 11, 1928. Serial No. 291,986.

In stores it has been the custom to advertise the sale of merchandise, such as wearing apparel for example, by means of an advertising card mounted in a rack supported by a pedestal and usually placed upon a counter or within a show window. Such a card frequently bears a legend indicating the time at which the sale occurs, another legend indicating the article of merchandise on sale and 10 a third legend relating to the price of the article. Whenever a change is made in the day or month of the sale, in the article on sale, or in the price, the entire card is usually thrown away, as it is unlikely that the precise combination of advertising matter thereon will ever be needed again. In large department stores the scrapping and replacement of such cards often entails an expense of thousands of dollars annually. To reduce this expense, 20 cheap cards are sometimes used. This policy is unwise, however, as such cards are unattractive and mar the appearance of the store. A sign in particular favor with high class establishments is a stout card having an attractive surface and bearing embossed legends. Such cards are clean cut and ornamental, but their greater cost and the necessity of scrapping large quantities of them renders their use very expensive to a large establishment. 25 It is an important object of the present invention to provide means whereby the different legends of a sign, of the character above stated, may be separately removed from the body of the sign and replaced by other legends 30 in accordance with changes in the advertising requirements, so that the scrapping of the sign may be avoided and so that the individual legends may be preserved and used repeatedly in different sign assemblies. 35

Other objects of the invention will appear hereinafter.

In the drawings:

Fig. 1 is a face view of my improved sign 45 card rack bearing one assembly of legend cards;

Fig. 2 a similar view of the upper portion of the rack with certain of the cards removed and replaced by cards bearing different 50 legends;

Fig. 3 a side edge view of the upper portion of the rack;

Fig. 4 a face view, upon a larger scale, of the card-holding frame prior to attachment to its supporting means; 55

Fig. 5 a vertical section, upon a still larger scale taken on the line 5-5 of Fig. 4;

Fig. 6 a horizontal section taken on the line 6-6 of Fig. 4; and

Fig. 7 a miniature view of three sets of legend cards for mounting successively in the frame. 60

The sign rack includes a card-holding frame 1. This frame comprises two face members 2, both of the same shape and size and disposed parallel with each other and in register. Each member is formed of sheet metal cut or stamped into an open structure slightly arched in contour at the top, straight at the bottom and converging downward slightly at the sides. An inwardly turned contour flange 3 is integrally formed upon each member and extends continuously along the top, along one side, and along the bottom of the member. It is omitted, however, from the opposite side. 65 Each member is also formed with three face openings 4, 5 and 6. These openings are horizontally elongated and located one above the other. They extend over most of the face area within the contour, leaving only a contour margin 7 and two narrow horizontal ribs 8 separating them. Around the margins of the openings the sheet metal is turned inwardly as at 9 to produce a beveled effect and to closely engage the cards which are to be 70 mounted within the frame. 75

Between the face members 2 are two sheet metal channel members 10 disposed horizontally directly between the opposed ribs 8. These channel members are inverted with respect to their cross section. Within the lower end of the frame 1 is another sheet metal channel member 11. This member bottoms directly against the flanges 3 and its sides bear against the inner sides of the frame 80 margins. The channel members 10 and 11 extend almost the full width of the frame. Within the upper end of the frame are three inverted U-shaped clips 12 spaced along the width of the frame and in contact with the 85 90 95 100

- inner sides of the margins 7 and the flanges 3. The channel members 10 and 11 and the clips 12 are secured to the frame members 2 by spot welding as indicated at 13. They 5 serve to hold said frame members in spaced relation, with the edges of the flanges 3 opposed, and their width is slightly greater than the combined normal width of the opposed flanges so that if there are any slight 10 irregularities in the edges of the latter they will not interfere with the assembling of the frame parts. The channel members 10 also divide the space between the frame members 2 into three horizontally elongated card-re- 15 ceiving pockets and form the bottoms thereof. These pockets open outwardly at one end through the unflanged side of the frame. At the opposite side of the frame they are closed by the flanges 3.
- 20 A threaded socket member 14 is mounted upon the lower end of the frame 1. This member is formed with a fork which straddles the frame midway the width of the latter and is secured thereto by spot welding. A 25 standard 15, provided with screw threads at its ends, has its upper end screwed into the socket member and its lower end screwed into a base 16. The frame 1, with its pedestal formed by the standard and base, forms a 30 portable card rack for standing upon a counter or within a show window.
- A plurality of advertising cards are provided for mounting within the pockets of the frame 1. In the present instance there are 35 three series of cards. In one series each card 17 bears a legend indicating the time at which a sale is to occur. It may, for example, indicate the day of the week, the month, the season, or may bear a legend such as "Annual" 40 or "Semi-annual". The cards of this first series may also bear the name of the store. The cards 18 of the second series bear legends indicating different articles of merchandise upon different cards. The cards of the third 45 series bear different legends relating to the price of the merchandise. This may be expressed in several ways, as by dollars and cents, or by indicating the percentage of reduction from the original price. I preferably 50 employ cards whose legends are stamped thereon by an embossing process. This process consists in superposing a sheet of thin material upon the face of the card and making impressions with sharp-edged type which 55 cut out the characters from the superposed sheet and secure them to the card by pressure around their edges. Such cards are neat, clean-cut and attractive. Other types of cards, may, however, be employed.
- 60 Each card 17 of the first series, bearing a time legend, is of a suitable form for mounting within the uppermost pocket of the frame 1 with its legend exposed through the opening 4 of one of the frame members 2. Each 65 card 18 of the second series, bearing a mer-

chandise legend, is of a form to mount in the middle pocket of the frame with its legend exposed through one of the openings 5. Similarly each card 19 of the third series, bearing a price-indicating legend, is formed 70 for mounting in the lowermost frame pocket with its legend exposed through one of the openings 6. Preferably each card of each series has a duplicate with the same legend, and the two are mounted in a pocket together, back to back, with their legends exposed through the face openings of both frame members 2. In Fig. 4 two cards are shown so mounted in the uppermost pocket. The cards are all inserted and removed 75 through the unflanged side of the frame. When inserted their marginal edges are covered by the frame margin 7 and by the ribs 8. Their exposed areas are neatly framed by the inturned bevel edges 9 of the frame. 80

When any one of the three sale conditions expressed by the advertising legends changes, the legend card relating thereto is removed and replaced by another card of the same series bearing an appropriate legend. For 90 illustration, the top and bottom cards shown in Fig. 1, relating to the day of the sale and the price of the merchandise respectively, have in Fig. 2, been replaced by other cards of their respective series bearing different day 95 and price legends. The card indicating the merchandise has not been disturbed. However this card may be removed and replaced by another card of its series when required. The cards of each series are interchangeable 100 and when a card is removed from the frame it is preserved for future use. By the provision of a suitable number of cards in each series a great variety of advertising set-ups can be had without the necessity of buying 105 a new card each time the advertisement is changed. In Fig. 7, to reduce the illustration I have shown only a few cards in each series. Each series, however may be extended to include as many cards as the establishment requires. Also the number of series may be varied and the frame formed accordingly with a greater or less number of card-receiving pockets. 110

While I have shown and described a practical and desirable form of my invention I do not wish to be limited strictly to this disclosure but reserve the right to make such changes as will lie within the scope of the claims. 115

What I claim is:

1. A display card rack comprising a pair of spaced, parallel face members each formed of a single sheet of metal and both of the same contour, disposed in register with each other in upright planes, integrally formed with inturned opposed contour flanges extending continuously along and substantially closing the top, bottom and one side of the frame but omitted at the opposite side, each 125

- face member being formed at its face to provide a slender outer margin extending entirely around the contour and with a plurality of slender horizontal cross strips, vertically spaced, dividing the space surrounded by said margin and defining with the latter a plurality of horizontally elongated face openings, the face openings in each member registering with the openings in the companion member and each member being turned inward along said margin and along said cross strips to produce a beveled effect around each opening; a plurality of sheet metal channel members horizontally disposed between the face members in positions between said cross strips of the two members, rigidly secured at their opposite channel sides to said strips and dividing the space between the frame members into a plurality of horizontally elongated card-receiving pockets opening endwise through said unflanged side of the contour to permit the insertion and removal of the cards; and means to support the frame upright.
- 25 2. A display card rack comprising a frame formed of a pair of spaced, parallel face members each formed of a single sheet of metal and both of the same contour, disposed in register with each other in upright planes, integrally formed with inturned opposed contour flanges extending continuously along and substantially closing the top, bottom and one side of the frame but omitted at the opposite side; a plurality of sheet metal channel members horizontally disposed between said face members, spaced apart vertically, secured at their sides to the face members and dividing the space between the face members into a plurality of horizontally elongated card-receiving pockets opening endwise through said unflanged side of the contour to permit the insertion and removal of the cards, each face member being formed with a plurality of face openings to reveal advertising matter upon the inserted cards and the marginal edges of the face members being turned inward around said openings to produce a beveled effect; and a pedestal to support the frame upright.
- 50 In testimony whereof I hereunto affix my signature.

FREDERIC D. COURTENAY.
